PNEUMATIC RELAY

This invention relates to instrumentation for process and energy control, and has particular reference to pneumatic systems in such instrumentation, and to pneumatic relay devices in such systems, such as shown in U.S. Pat. No. 3,105,508 to Bowditch.

Relays are key elements in such pneumatic systems, as devices for providing operating forces in response to small pilot pressures. For example, a fluid pressure may be used to control a fluid power stream. A useful relay form is one which uses a diaphragm to operate a valve, in response to the pilot pressure on the diaphragm. Sensitivity and accuracy of response and operation is necessary in the handling of relatively large forces by small signal forces in such devices, the signal forces often being provided by back pressures from a highly sensitive pneumatic nozzle-baffle device. In the past such devices have been expensive to manufacture and assemble to the necessary precision requirements of control instrumentation.

The device of this invention provides simple and inexpensive means of such manufacture, assembly, and adjustment, while maintaining the necessary sensitivity, accuracy of response, and operational integrity.

This invention provides, for this purpose, a special combination of a sandwich form of diaphragm and a leaf-spring grounded adjustment zero bias device. These devices are in themselves, each a subcombination of this invention. These devices, further, are simple stamping formations, with location and adjustment problems minimized.

The zero bias device provides grounded adjustment means. This means that the forces of adjustment do not disturb the adjustment except as directly applied to adjustment. For example, this device uses a grounded screw for zero bias adjustment. No amount of pressure down on the screwhead has any effect on the adjustment. Only rotation of the screw accomplishes adjustment. Thus this device lends itself to automatic machine manufacture, assembly, and calibration or adjustment. The adjustment spring of this device thus lends itself to devices other than relays, and to calibrating as well as direct zero bias adjustment in a concept applicable to fully automatic manufacture.

The relay of this invention is provided with an adjustable valve seat, and is a low-bleed device, saving in air waste.

Other objects and advantages of this invention will be in part apparent and in part pointed out hereinafter and in the accompanying drawings wherein:

FIG. 1 is an at rest perspective of a zero bias spring structure according to this invention;

FIG. 2 is a further view of the structure of FIG. 1, with the spring variously bent, in an operating condition;

FIG. 3 is a schematic of the spring of FIGS. 1 and 2, in the condition of FIG. 2;

FIGS. 4 and 5 are showings of an alternative spring structure according to the views of FIGS. 1, 2 and 3;

FIG. 6 is a plan view of a further variant of the zero bias spring structure according to this invention;

FIG. 7 is a perspective of an overall relay structure according to this invention;

FIG. 8 is a central section of the relay, taken on line 8-8 of FIG. 7;

FIG. 9 is a plan view of a slotted diaphragm metal plate sandwich assembly according to this invention; and

FIG. 10 is a section of the diaphragm assembly, taken on line 10-10 of FIG. 9.

In FIG. 1, the leaf-spring 10 is a one piece sheet of metal, formed by stamping or cutting for example, into an H form flexure with side leg strips 11 and 12, with a bridge 13 therebetween, and tongues 14 and 15 extending between the legs 11 and 12, from the bridge 13. The whole device is flexible, and an adjustment screw hole 16 is provided in the tongue 14. The FIG. 1 showing is in 'at rest' flat condition.

The operational form of the leaf-spring 10 is illustrated in FIG. 2. Each of the H leg ends is rested on a fixed ground as at 17. These ground supports, as provided by the body of a relay, for example. The H leg ends are free to bend and possibly slightly slide on their ground supports as the overall flexure is bent. An adjustment screw 18 is also grounded, that is, it is threaded into the fixed ground 17. The tongue 14 is biased upward by its own resilience against the underside of the head of the screw 18. A dotted circle 19 on the tongue 15 indicates the location of, for example, a relay valve ball as the device to which the variable pressure of the spring is applied, in this case as a zero bias for the relay.

As illustrated in both FIG. 2 and FIG. 3, as the screw 18 is rotated so as to progress downward into the ground support 17, the tongue 14 is depressed. This results in downward bowing in the side strips 11 and 12, and downward bending of the tongue 15, to a greater extent than the side strips because the outer end of the tongue 15 is not grounded and the side strip ends are grounded.

Variation of movement of the tongue 15 per unit of adjustment of the screw 18 may be accomplished by locating the screw closer to or further away from the flexure bridge 13.

It is notable that downward pressure on the head of the screw 18 has no effect on the flexure force or adjustment. It is only when the screw is rotated that spring bias change occurs. This device therefore usefully lends itself to simple and precise adjustment, and to automatic machine assembly and calibration or adjustment of a pneumatic relay or other instrument device. Thus, this flexure is applicable to a wide variety of instruments.

FIG. 3 indicates the location of a diaphragm 20 and the valve ball 19 movable thereby as related to this flexure device in an application such as a pneumatic relay.

FIG. 4 indicates the leaf-spring structure of FIGS. 4 and 5, and that of FIG. 6, as alternatives to the structure of FIGS. 1, 2 and 3, are given like reference numbers for like elements. The structure of FIGS. 4 and 5 differs in that the side strips 11 and 12 are joined at the output end, that is the end adjacent the tongue 15, to provide a screw 21 as a grounded adjustment for coarse adjustment, instead of the two fixed grounds 17 for the like ends of FIG. 2 side strips 11 and 12.

The FIG. 6 structure is a desirable form for the pneumatic relay of this invention. The tongues 14 and 15 are of different lengths for more effective operation for this application, and side knobs 22 and 23 are used as locaters in suitable recesses (not shown) in the relay body to prevent undue planar movement of the overall flexure device.

FIG. 7, the externals of a pneumatic relay according to this invention include a main body 24 and a cover plate 25. A zero bias spring structure 10 is shown in a recess in the body 24, this structure being of the nature of those illustrated in FIGS. 1 through 6. This relay has an A/S (air supply) power in opening at 26, a power exit at 27, a vent at 28, and a pilot signal input through the cover as indicated at 29, for example, from the back pressure of a nozzle-baffle device 30.

FIG. 8 details the interior of the relay of FIG. 7. A suitable cover or panel 31 is used to close off the zero spring recess (not shown in FIG. 7). The power fluid system starts at the input 26, into a chamber 32, containing the zero spring 10, past the valve ball 19 when it is lifted from its seat by the diaphragm 20 through a valve stem 33 attached to the diaphragm but unattached to the ball 19, and then to the power outlet 27. The valve comprises the ball 19, an adjustable conical seat 19' for receiving the ball, and the valve stem 33.

The diaphragm assembly 20 divides a housing chamber into an inner subchamber 34 and an outer subchamber 35. The inner subchamber 34 is open to the power stream when the valve is open (when the ball 19 is lifted from its seat), and the vent to atmosphere is provided from the inner subchamber 34, at 28.

The outer subchamber 35 is part of a pneumatic system leading from the air supply 26, through a restrictor 36 into

subchamber 35 and out to the nozzle-baffle device 39, as a nozzle bleed supply therefor by way of the housing opening 29. Back (pilot) pressure from the nozzle, when restricted by the baffle, builds up in the outer subchamber 35, to move the diaphragm and lift the valve ball 19 to allow passage of power flow. Thus, the pressure point of valve opening depends on the adjustment of the spring plate 10 as it applies a resilient bias against the valve ball 19 to hold it in its valve seat.

The diaphragm assembly 20, FIGS. 8, 9 and 10, comprises a flexible, thin metal plate 37 sandwiched with a rubber or rubberlike backing sheet 38. This rubber backing allows for assembly of the valve stem 33 without the necessity of highly precise and expensive locating and sealing of the stem in the diaphragm assembly, and provides for self-aligning seat action in the associated valve.

In FIG. 9, the metal diaphragm plate 37 is shown with relieving radially a arcuate slots 39 therethrough which provide an inexpensive structure providing the necessary response and sensitivity in a simple manner by allowing greater and freer movement of the center of the diaphragm. The rubber sealing sheet 38 covers and seals the slots 39. A center hole 40 is used to mount the valve stem 33, and an opening 41 through the assembly is part of the pneumatic passage from the air supply into the outer subchamber 35, FIG. 8.

With the simplicity and inexpensiveness of this overall structure, the relay according to this invention lends itself to miniaturization and low pressure pneumatic uses and systems.

This invention therefore provides a new and useful pneumatic relay in a combination of sandwiched diaphragms and grounded leaf-spring zero bias means, lending itself to simple and inexpensive manufacture assembly and adjustment while maintaining the sensitivity and operational integrity necessary to control devices of modern instrumentation.

As many embodiments may be made of the above invention, and as changes may be made in the embodiment set forth above without departing from the scope of the invention, it is to be understood that all matter hereinbefore set forth and in the accompanying drawings is to be interpreted as illustrative only and not in a limiting sense.

I claim:

1. For use in process and energy control instrumentation, a pneumatic relay wherein a diaphragm valve is operable by a pilot pressure to pass a fluid power stream through the relay;

said relay comprising a housing, a fluid power stream passage through said housing, a valve in said power stream passage, a diaphragm chamber in said housing, a diaphragm in said chamber forming two subchambers therein, a stem of said valve secured to said diaphragm for movement therewith to operate said valve, the inner one of said subchambers being open to said power stream passage downstream of said valve, a vent to atmosphere from said inner subchamber, a restricted pneumatic supply inlet to the outer one of said subchambers, and a

5

restrictable outlet from said outer subchamber, whereby restriction of said outlet results in diaphragm pressure in said outer subchamber and consequent opening of said valve, said diaphragm comprising a flexible metal plate with relieving slots therethrough, sandwiched with a sheet of fluid sealing means closing said slots; and wherein said diaphragm metal plate is a thin flat sheet with said relieving slots radially arcuate essential from the center of said sheet.

10

2. For use in process and energy control instrumentation, a pneumatic relay wherein a diaphragm valve is operable by a pilot pressure to pass a fluid power stream through the relay; said relay comprising a housing, a fluid power stream passage through said housing, a valve in said power stream passage, a diaphragm chamber in said housing, a diaphragm in said chamber forming two subchambers therein, a stem of said valve secured to said diaphragm for movement therewith to operate said valve, the inner one of said subchambers being open to said power stream passage downstream of said valve, a vent to atmosphere from said inner subchamber, a restricted pneumatic supply inlet to the outer one of said subchambers, and a restrictable outlet from said outer subchamber, whereby restriction of said outlet results in diaphragm pressure in said outer subchamber and consequent opening of said valve, said diaphragm comprising a flexible metal plate with relieving slots therethrough, sandwiched with a sheet of fluid sealing means closing said slots; and

15

said relay including a leaf-spring generally in the form of an H, with a tongue between each set of H legs, from the crossbar of the H, with each of the H legs grounded at its end, one of said tongues adjustable transversely of the plane of the H by grounded adjustment means, and the other of said tongues applied to said valve as adjustable operating zero pressure biasing means therefor.

20

3. In a fluid pressure instrumentation device wherein a signal pressure is used to actuate an operations pressure system and wherein a diaphragm structure is used to isolate said signal pressure, a diaphragm structure comprising a flexible sheet having slots therethrough from a central area to a peripheral area in terms of the operative area of said sheet which is exposed to said signal and operating pressures on opposite sides thereof, said slots being restrictive to isolate said pressures on said opposite sides of said sheet, the total planar solid area of one side of said sheet being substantially larger than the slot area in the same planar consideration, wherein valve means is operable by said signal pressure through said diaphragm, and including H form leaf-spring is used to provide a bias on said valve means, said H spring being grounded at its 30 extremities and having tongue formations from the H crossbar, one tongue being adjustable by grounded adjustment means and the other tongue providing the application of said bias.

35

40

45

45

50

4. In a fluid pressure instrumentation device wherein a signal pressure is used to actuate an operations pressure system and wherein a diaphragm structure is used to isolate said signal pressure, a diaphragm structure comprising a flexible sheet having slots therethrough from a central area to a peripheral area in terms of the operative area of said sheet which is exposed to said signal and operating pressures on opposite sides thereof, said slots being restrictive to isolate said pressures on said opposite sides of said sheet, the total planar solid area of one side of said sheet being substantially larger than the slot area in the same planar consideration, wherein valve means is operable by said signal pressure through said diaphragm, and including H form leaf-spring is used to provide a bias on said valve means, said H spring being grounded at its extremities and having tongue formations from the H crossbar, one tongue being adjustable by grounded adjustment means and the other tongue providing the application of said bias.
